INLET AIR OPENING OF JET PROPELLED PLANES

Douglas K. Warner, Sarasota, Fla.

Application May 26, 1943, Serial No. 488,800

4 Claims. (Cl. 244—13)

1

The present invention relates to improvements in operating means for airplanes of all kinds, although since it has particular reference to propulsion means for jet propelled compression planes I have described it with particular reference to that type of plane.

The inherent problem in an efficient jet propelled plane is that the opening which receives the air required for propelling the plane should be reduced in size as the plane moves faster. For example with the same pressure conditions fore and aft of the inlet opening some 40 times the weight or cu. ft. of air would pass thru an opening moving at 400 miles an hour as one moving at 10 miles per hr. The weight of air required to propel the plane increases in a lesser ratio than this and at speeds of 400 miles per hr. and above it is necessary to slow the air down before allowing it to contact moving propeller blades in order to prevent the air flowing over the tips of those blades from exceeding the speed of sound. If the air is not slowed down before reaching the propeller or fan an enormous drag will be set up, accompanied by terrific shock stresses in the propeller blades. Accordingly even barring efficiency considerations favored by reducing the inlet opening at very high speeds it becomes essential that the inlet opening be smaller than the fan area at high speeds. At low speeds an entrance to the air intake of lesser area than said fan area decreases the efficiency and capacity of the fan. It is possible by stream lines to restrict the passage between the entrance and the fan without causing that same decrease in efficiency and capacity resulting from an entrance opening as small as said passage restriction. Accordingly the desired results may be obtained by changing the shape of the opening ahead of the orifice throat, in such a manner that at low plane speeds the air is speeded up over a lip to the orifice and then slowed down in a diverging nozzle leading to the fan while at high speeds the lower lip of the orifice entrance is removed and the air enters without initial velocity gain and is just slowed up behind the orifice. Removal of said lower lip greatly reduces the head resistance at high speed in addition preventing excessive air speeds at the propeller blades.

In a good airfoil while the lift coefficient increases from .4 to 1.6 the drag increases from .02 to .20. This means that a plane requiring a lift coefficient of 1.6 at 100 miles per hr. requires only $\frac{1}{4}$ as much at 200 miles per hr. and accordingly the drag coefficient is $\frac{1}{16}$ as great and the actual

2

drag only $\frac{1}{16}$ as great thereby requiring a thrust less than half as much as when flying half that speed at the same altitude. The complete compression plane has a lift coefficient many times greater than the normal airfoil cited above but has the same characteristics of requiring lower thrust at high speed. The thrust from a jet equals the weight of air times its rearward velocity. If the velocity of the jet remained constant (it doesn't), less than half the weight of air would have to be handled at twice the speed while a fixed front opening would be taking in twice as much air at the higher speed, this indicating a marked decrease in frontal opening is required. Actually the jet velocity relative to the ground does not stay constant but decreases as velocity of the plane increases. Let us take for example a compression plane whose fan at starting gives an air speed of 200 miles per hr. By diffusion nozzles below the plane this is converted into a pressure lift of 20.025 inches of water or $104\frac{1}{2}$ lbs. per sq. ft. plus a suction lift above the wing immediately behind each slot of about half that amount. The pressure lift extends only under the central portion of the wing resulting in a total average lift at zero velocity of approximately 116 lbs. for each square foot of all wing surface. If the plane has a central portion 7 ft. wide and 34 ft. long and spread of 27 ft. the central or pressure area is 238 sq. ft. and the wings 120 sq. ft. giving a total area of 358 sq. ft. and a lift at zero velocity of 42,700 lbs. when developing 306 H. P., to theoretically expel 1615 cu. ft. of air per second at 200 miles per hr. from the slots in the top of the wing surface, giving the plane a thrust of 35,300 lb. ft./sec. and an acceleration to the plane of .83 ft. per sec./sec. if loaded with 21.35 tons. With this acceleration about 3 minutes are required to reach a speed of 100 miles per hr., at which speed the motor speed has advanced 10%, its power risen to 326 H. P., the air handled 1775 cu. ft. per sec., the thrust 23,300 lb. ft. sec., the drag on the plane due to air friction and no induced drag while skimming, 1,000 lbs., and the remaining thrust available for acceleration 22,300 lbs., so requiring about 6 minutes more to accelerate to 200 miles per hr. before which time the flap under the nose of the plane has folded back, the tail has lifted allowing air to escape rearwardly in back and the engine has increased its speed 30% above starting R. P. M.

It will be noted that while the propulsive efficiency of the jets above the wing increases with increased speed, their lift decreases while the lift

on the forward part of the wing mounts with the square of the speed or with the angle of attack. On the other hand the pressure lift due to expanding the prop slip stream in diffuser nozzle or nozzles below the plane increases with increase of speed, its center of pressure moving steadily rearward with increase of speed, and so offsetting the opposite motion (of the C. P.) on the top of the wing. The difference in travel between the two must be corrected by changing the percent of openage of the various jets, or by pumping fuel from rear tail tanks to the bow floats, or by changing the attack angle or of the pilot wings, or by all three or two of these operations.

It should be noted that there is a marked distinction between openings in the top and bottom surfaces of the plane. Entrance to the upper jets is by an orifice with a bluntly rounded lower edge and smooth wall upper surface and no appreciable length so that maximum air velocity may be obtained where not over two atmospheres pressure is maintained inside the plane. The lower nozzles however must be designed to slow the air down by long diffusion passages so that it will emerge at the same velocity at which the air is moving on the lower side of the plane. The result of slowing down the air leaving the fan is to build up pressure and as long as that compressed air remains under pressure it will impart a definite upward lift on the bottom of the plane. The duration of what might be called an explosive lift extends backward from the tail end of the nozzle in decreasing magnitude, the distance backward and magnitude being proportional to the square of the plane's speed. This accordingly is responsible for the rearward movement of the pressure center on the bottom of the plane which is so highly important in offsetting the opposite motion of the C. P. on the top surface due to the rapidly diminishing proportion of lift due to jet action on the top surface, as compared with lift derived from forward motion. It should be noted that the principal bottom lift is not caused by weight of air ejected downwardly with consequent reaction upward but by creating an instantaneous pressure wave below the plane which even though emitted only under the central portion when not confined between the runners by a surface, spreads laterally out under the tail wing. It might be likened to the lift developed by exploding flak beneath a plane and as clarification, I mention the flak lift as something frequently recognized and described. This pressure exists only in a very thin strata of air beneath the plane. It vanishes while the plane moves half its length while traveling at extreme speed, except when plane is on a surface. The propulsion efficiency of the diffuser jets in the bottom surface is always higher than that of the velocity jets in the top surface, its efficiency at high speed flying almost 100% and while skimming practically limited only by the craftsman's ability to restrict air leakage from the confined space below the plane. I also mention as in former applications that the efficiency of the engine is increased because all the radiated and exhaust heat and velocity energy is introduced into air brought to considerable pressure elevation by the propulsion fan and in the resulting expansion of that air from either upper or lower orifices the heat is an important asset, capable, especially at very high altitudes, of more than doubling the power obtained from burning a given weight of fuel in the engine, and in some instances where additional fuel is burned directly in the air compressed by

the fans to two or more atmospheres of adding ten fold to the normal engine power.

As originally cited a very important element in maintaining high efficiency in such a jet propelled plane is the ability to change the areas of the openings where the air enters and leaves the plane in a manner that does not impair the strength or stream lines of the plane and it is to this element that I am directing this application.

10 Figure 1 shows a $\frac{3}{4}$ view of the compression plane from above.

Figure 2 shows the front portion of the same plane with the bow flap swung back under the plane on hinge 5.

15 Figure 3 shows a section thru the center of the plane.

Figure 4 shows the piston and tubes which operate the bow flaps.

In Figure 1 it can be seen that air enters into 20 the compression plane in the opening below the leading edge 22 and above the hinge 5. After being speeded up by fan blades 9 shown in Fig. 3 it leaves through upper slot 31 and lower diffuser 28 and thru slots in back of fuselage controlled by the forward airfoils 15 the rearward airfoils 17 and lateral airfoils in tail wing 19 and 32.

A passenger cabin is located each side of the inlet opening with windows 12 opening in to air inlet passage as well as to the outside so that unobstructed view in all directions is obtained from either cabin, either thru the opening ahead, or directly outside, or thru the windows of the opposite cabin.

Auxiliary air foils 18 are controlled from the 35 cabin to deflect air over the main wings which are at the rear. These normally are set at a small negative angle of attack in order to increase the air velocity over the forward part of the rear wing and maintain that velocity for a longer distance.

40 The higher the attack angle at which the plane may be flying the greater the negative angle of the pilot wing should be for maximum efficiency but the pilot wing may be used as a stabilizer as well as for adding 50% to the lift of the main wing.

45 Changing the attack angle of the pilot or auxiliary airfoil moves the center of pressure of the main wing so providing the pilot with additional means of controlling the flight path of the plane, using these in place of ailerons or elevators.

50 The main controls however which are actuated by the pilot's wheel or stick are the slot airfoils 15, 17, 19 and 32. Moving the wheel forward will close the slot openings at the leading and trailing edges of airfoils 15 by rotating them

55 counterclockwise on their axis pins located at about $\frac{1}{3}$ their chord from their leading edge. The same motion turns airfoils 17 clockwise and opens all the rearward slots. Controls on the wheel make it possible to decrease the extent of

60 opening of all slots or entirely close them all. To make a right bank and turn left slot 32 is closed in the left wing and slot 19 opened wider in right wing. This stops the jet thrust and lift on the left side and increases it on the right side so giving bank and turn in one operation and without the counteracting forces usually produced by rudder and ailerons.

In Fig. 3 it will be seen that the under lip of the plane, 7 is set rearward of the upper lip (or nose of the plane) 33, separated therefrom by the distance A. From the forward edge of 7, hung on hinge 5, is upper flap 4, extending downward and forward to hinge 1 which is directly below edge 33 a distance B which is considerably greater than distance A. Lower flap 3 is hinged at 1

to upper flap 4. Its trailing edge drags over the surface below slipping snugly past the vertical inside walls of the cabins and while free to move up and down over the waves or rough surface, securely prevents leakage of compressed air under the plane from moving forward. As long as the pressure under the plane remains higher than the pressure due to forward motion on the front of plates 3 and 4 and hinge 1 will remain forward as shown but when the speed of the plane has produced enough additional lift to raise the tail of the plane and allow the air pressure below to escape rearward the forward pressure against these flaps will be removed to an extent that will permit the air in front of the plane to blow the flaps back under the body. Normally, pipe or cylinder 26, is open to the outside air thru 3 way cock 34, and piston 25 and hollow rod 24 may move freely back due to the air pressure on flaps 3 and 4, and these flaps will form a smooth bottom for airfoil 7 when in their retracted position. However in the emergency of engine failure in high flight the cock 34 is turned so as to close communication with the outside air and connect cylinder 26 with liquid CO₂ flask 30. The liquid will flow down into the cylinder 26 from the flask and the heat will evaporate the liquid and push piston 25 and rod 24 forward so pressing hinge 1 forward with flap 4 and thereby greatly increase the size of the air opening leading inside the plane. The dotted lines to point 6 show where a maximum force resists the motion of piston 25 requiring a force of over 1000 lbs. per sq. inch to push the piston forward. Near the end of the stroke the resistance decreases and in order to prevent the piston blowing out the end of the cylinder cap 36 is screwed to the end of cylinder 26. The cap is fitted with compression rings 37 which contract on rod 24 as shown and prevent leakage of air from the annular passage space 35 formed between cylinder 26 and rod 24. As the piston is forced forward in the cylinder by CO₂, air is compressed in space 35 until the pressure becomes so enormous that it overcomes the pressure and inertia tending to drive the piston forward. However a momentary stop due to this counterpressure at the end of the forward stroke flutters rings 38 on piston 25 from their seats at varying sides of the ring slots and quickly equalizes the pressures in 35 and 26 and the piston is then held tight against cylinder head 36.

This forward motion of flap 4 will produce a large drag forward slightly below the C. G. and will so tend to dive the plane which because of the engine failure had lost a lot of lift from the air jets back of the C. G. which would otherwise have caused the plane to increase its attack angle. The main function of this action is however to resupply the air pressure formerly furnished by the engine and its fan even tho it must be obtained at the cost of additional air drag greater than the propulsive jet power derived from that drag. This procedure restores to the pilot most of his original control by the manipulation of the slot airfoils and permits the plane to descend in a long glide instead of at once going into a stall which as mentioned in a former application was a difficulty accompanying the enormous load carrying ability of the compression plane.

As already explained the air opening of the compression plane should be reduced as the speed increases in order that the weight of air handled by the fan shall not increase too rapidly and in order that air speed over the fan blades shall not exceed the speed of sound at any point and so

as to eliminate in most cases the need for changing the pitch of the fan blades, thereby simplifying and reducing the cost of the propulsion fans, and finally so that air speeds approaching 90% of the speed of sound may be obtained without forming a compressibility burble either on the wings or the propeller blades. The ordinary plane will form such burbles on the propeller blades at speeds half as fast as sound because the propeller 10 in its helical path thru the air travels twice as fast and far as the plane if the tip has an effective pitch of 30 degrees. A pitch that high puts almost the whole blade beyond the stall point at slow speed takeoff, making short takeoff runs impossible in conjunction with high top speeds where the ordinary fixed pitch propeller is used. Even where the propeller pitch is adjustable it is impossible to build a propeller with efficient attack angles at both take off and very high speeds. 15 Take for example an 11 ft. propeller mounted in a plane that takes off at 100 ft. per sec. or 68 miles per hr. In such a plane the propeller R. P. M. should be reduced from 1720 R. P. M. at take off to 1350 R. P. M. at maximum speed of 420 miles per hr. Since the engine will develop less H. P. 20 at the lower R. P. M. required by sound effects on the prop, unless a gear shift is provided, maximum engine H. P. can not be obtained at take off and highest speed. Also while a pitch advance of 33.1° is required at the high speed at the propeller tip a 51.3 degrees advance is required at 30% of blade length, or 18.2 degrees more than at the tip. Since the efficient attack angle variation of propeller airfoils is limited to less than 25 6 degrees the variable pitch propeller must be very inefficient over the circle of the inside 75% diam. in addition to requiring a disastrous reduction of R. P. M. at 420 miles per hr. The much better procedure is to cover the 75% inside diameter of 30 the prop circle with a streamlined deflector, increase the number of blades and increase the density of the air which the blades handle at high plane speeds; by decreasing its velocity before it touches the blades. By doing this the R. P. M. 35 does not have to be reduced so much, and because the blades will be working on denser air the slightly lower R. P. M. will be accompanied by an increase in engine torque so exactly fitting the engine power curve. This again requires a reduction of air inlet opening in front of the plane with increase of speed, the subject of this invention.

Figure 1 shows the compression plane with the flap forward increasing the entrance area and 40 Fig. 3 shows the flap in the same position. Fig. 2 shows the flap in the rear flying position as it is also shown in the upper dotted lines of Fig. 3. When the flap is back the opening is similar to that of the Hanley Page slot. It has little frontal area, and with the fan behind it, inside the plane, causes no drag. With the flap forward there is the large entrance B and A becomes the throat of a Venturi passage.

I claim:

45 1. The combination in an airplane having a bottom surface pressure supported, with the propulsion fan of a flying machine of a diffusing passage of gradually and continuously increasing area rearwardly forward of said fan and a flap hinged at the lower forward portion of said passage said flap being extendable in either a forward direction or in a rearward direction beneath and adjacent to the bottom surface of said flying machine and power means for advancing said 50 flap from a rearward to a forward position.

2. The combination, with the propulsion device of a flying machine of a passage of continuously, gradually increasing area rearwardly, from a forward opening, and flap means for extending the length of said passage forwardly of its normal opening with a forwardly diverging passage and power means for advancing said flap from a rearward to forward position.

3. In an aircraft having a pressure chamber beneath the lower surface thereof and wholly open to the air and to the water surface beneath said aircraft, the combination with the fan propulsion device of said aircraft of a passage of continuously, rearwardly, slowly increasing area ahead of said device, a flap hinged below the lower forward portion of said passage in a manner whereby said flap may extend rearwardly close below the lower surface of said aircraft or extend forwardly thereby increasing the length and changing the taper of said passage, while at the same time providing an air seal for compressed air beneath the aircraft when said aircraft is close to the surface, and whereby said flap in flight and away from a surface forms an elevator assisting in preventing stall by making said aircraft dive, and passages rearward of said propulsion device communicating between said device and the air above and below said aircraft, said passages communicating with the air above discharging rearwardly in contracting passages, 30

and the passages communicating with the space below the aircraft having increasing area rearwardly.

4. In a combination, as in claim 3, means comprising said pressure chamber and for permitting blowing said flap forward by air pressure which said propulsion device creates below said plane.
